CLOSURE AND TAPPING CONSTRUCTION George Donald Flaitch and Joseph E. Smith, Jr.,
Philadelphia, Pa.

Application May 18, 1953, Serial No. 355,676

2 Claims. (Cl. 217—99)

The present invention relates to closure-and-tapping mechanism for barrels, drums and other containers having such novel closure-and-tapping mechanism, and it relates more particularly to a mechanism for introducing a compressed gas (as, for example, air or carbon dioxide) into the barrel or the like and for removing the liquid contents (as, for example, beer) under pressure.

An object of the present invention is to provide new and improved closure-and-tapping mechanism for barrels, drums and other containers.

Another object of the present invention is to provide a novel closure-and-tapping mechanism which is relatively simple and inexpensive to manufacture and which is sturdy and dependable in operation and which facilitates cleaning, inspection and re-filling of the barrel or the like.

Another object of the present invention is to provide a container having a new and improved closure-and-tapping mechanism.

Other objects and advantages of the present invention are apparent in the following detailed description, appended claims and accompanying drawings.

The present application is a continuation-in-part of our co-pending application Serial No. 34,728, filed June 23, 1948, and now Patent No. 2,638,914 and issued May 19, 1953.

Generally speaking this application is directed to a novel closure-and-tapping mechanism for a barrel or the like which includes a bung-receiver for operatively receiving a bung removably secured therein, said bung-receiver being removably fastened within a bung-flange of a barrel, and also to barrels or containers comprising said novel closure-and-tapping mechanism.

An important feature of the present invention is the novel construction which permits the bung-receiver to be quickly and easily disconnected from the bung-flange after the barrel or the like has been emptied, so as to provide a relatively large opening to facilitate cleaning, inspection and refilling of the barrel prior to re-use thereof, and which permits the bung-receiver to be easily re-connected to the bung-flange after the cleaning and inspection has been completed. Although the barrel may be filled (with beer or the like) through the conventional bung hole (generally located on the circular side of the barrel, the barrel having two bungs when the bung-receiver carrying a bung is in position in the bung-flange), the filling may be accomplished through the large-diameter opening of the bung-flange of the present invention prior to the connection thereto of the bung-receiver.

For the purpose of illustrating the invention, there are shown in the accompanying drawings a form thereof which is at present preferred, although it is to be understood that the various instrumentalities of which the invention consists can be variously arranged and organized and that the invention is not limited to the precise arrangements and organizations of the instrumentalities as herein shown and described.

2

Referring to the accompanying drawings in which like reference characters indicate like parts throughout:

Figure 1 represents a view, partly in elevation and partly in vertical cross-section, of the present invention with the bung removed from the bung-receiver and a valve-mechanism inserted within the bung-receiver, the bung-receiver being connected to the bung-flange.

Figure 2 represents an "exploded" perspective view showing the bung-receiver disconnected from the bung-flange.

Figure 3 represents a fragmentary vertical cross-sectional view of the bung-receiver and the valve-connector in the first stage of interconnection between the bayonet portions of the valve-connector and the bayonet portions of the bung-receiver.

Figure 4 is a horizontal cross-sectional view taken generally along line 4—4 of Figure 3.

Figure 5 is a horizontal cross-sectional view taken generally along line 5—5 of Figure 6.

Figure 6 represents a fragmentary vertical cross-sectional view of the bung-receiver and the valve-connector in the final stage of interconnection.

Figure 7 represents an enlarged, vertical cross-sectional view of the bung-flange and the bung-receiver; with the bung-receiver partly inserted into the bung-flange.

Figure 8 represents an enlarged, vertical cross-sectional view showing the bung-receiver and the bung-flange fully interconnected, with the bung inserted in position within the bung-receiver.

30 Referring generally to Figures 1 through 8 a bung-flange designated 20, formed of metal or the like, may be permanently attached or affixed to the sheet-metal end-wall 21 of a drum or barrel or like container; the end-wall 21 being provided with an annular stiffening or reinforcing rib or head 22 in radially spaced relation to container hole 23. The bung-flange 20 includes a flat circular bottom 24 which extends radially outwardly beyond the periphery of the hole 23 and which is permanently affixed (by welding, soldering or the like) to the container end-wall 21. In the case of wooden containers or drums, the bottom 24 of the bung-flange 20 can be affixed to the drum end-wall by suitable means, such as screws.

45 The bottom 24 of the bung-flange 20 is provided with a circular opening 25 which is in alignment with the hole 23 in the end-wall 21 of the container. Circular opening 25 is of smaller diameter than hole 23 of the container.

The bung-flange 20 also includes an upstanding collar 26 which has a generally cylindrical outer wall 27.

50 Collar 26 is provided with an uppermost generally circular inner surface 28 and a lowermost polygonal inner surface 29; the surfaces 28 and 29 being separated by a generally circular locking groove 30. The uppermost circular surface 28 has a plurality of notches 31 in axial alignment with the corners of polygonal surface 29.

A horizontal bung-receiver seat 32 intervenes the vertical polygonal surface 29 and circular opening 25.

55 The bung-receiver designated 33 is constructed and arranged to be removably mounted within bung-flange 20. Bung-receiver 33 includes a generally cylindrically-shaped body-portion 34 which may be formed of metal or the like, provided with a bottommost tapered portion 19. The cylindrical body-portion 34 is provided with an upper, generally flat head 35, the peripheral outline of which corresponds to and is adapted to cooperatively mate with the polygonal inner surface 29 of the collar 26 of bung-flange 20 described above.

60 Upstanding ears, tabs, or projections 36, each having axially inclined undercut inner surfaces 37 on the radially inner side surfaces thereof are provided at the corners of the head 35.

65 The cylindrical body-portion 34 includes a circumferen-

tial groove 38 on the outer surface thereof (see Figure 3).

An O-ring 39 of rubber or other compressible material is axially slidably mounted within circumferential groove 38 and when in position (see, for example, Figure 8) furnishes a fluid-tight and air-tight seal between the bung-receiver 33 and bung-flange 20.

Bung-receiver 33 is provided with an axial bung-receiving channel 40 adapted to removably receive a conventional bung or plug 41 of wood or the like. When bung 41 is operatively disposed within bung-receiving channel 40 as shown in Figure 8, a fluid-tight and air-tight sealing of bung-receiving channel 40 is effected.

A generally C-shaped locking-ring 42 of resilient metal or the like, such as spring-steel, having a normal diameter somewhat greater than the diameter of the locking groove 30 connects the bung-receiver 33 to the bung-flange 20.

The interconnection is effected by first compressing locking ring 42 (so as to bring its ends closer together and thereby reduce its diameter) and then fitting locking ring 42 into head 35 within the undercut inner surfaces 37 of the ears 36 in the manner shown in Figure 7. The bung-receiver 33 is in the position shown in Figure 2 with portions of the locking-ring 42 protruding radially outwardly beyond the straight edges of the head 35 between ears 36. The diameter of the so-compressed ring is less than the diameter of the circular inner surface 28 of collar 26 of bung-flange 20.

The tapered portion 19 of bung-receiver 33 is then lowered into the collar 26 of bung-flange 20 through the hole 25 until the cylindrical body-portion 34 enters hole 25 and O-ring 39 is disposed within hole 25. In this position, shown in Figure 7, the locking ring 42 extends radially beyond the straight sides of the polygonal head 35 and is seated on the seating surface 30a (see Figure 2) between the notches 31. The upper surface of the head 35 and the locking ring 42 are radially aligned with the locking groove 39 and the upstanding ears 36 are fitted within the notches 31.

Thereafter, the bung-receiver 33 is moved still further downward in respect to bung-flange 20; the seating surface 30a between the notches 31 preventing corresponding downward movement of the locking ring 42 and as a result the locking ring 42 remains in the same horizontal plane as the locking groove 39 while the ears 36 move downward relative thereto until the locking ring 42 clears the tops of the ears 36 and then springs outwardly into the locking groove 39 above the ears 36.

Figures 1 and 8 show the so-seated locking ring 42 overlying the tops of ears 36 and preventing upward movement of the bung-receiver 33 relative to the bung-flange 20; the bung-receiver 33 being thereby locked in position within the bung-flange 20. The position of the locking ring 42 adjacent the undercut inner surfaces 37 of ears 36 prior to being positioned in locking groove 30 is shown in dotted line in Figure 8.

The upper portion of bung-flange 20 and the exposed top surface of interconnected bung-carrying bung-receiver 33 can be covered by a tearable metal cap or seal (not shown) affixed to outer wall 27 of bung-flange 20.

When it is desired to remove the bung-receiver 33, a small screw driver, knife or other pointed tool may be inserted into one of the notches 31 to pry the locking ring 42 out of the locking groove 39 whereupon the bung-receiver 33 may be lifted out, so that the relatively large-size opening 25 in the bung-flange 20 is exposed, to facilitate cleaning and inspection of the drum or barrel or the like.

When it is desired to utilize the drum, barrel or container of the present invention containing the bung 41 in place within the bung-receiver 33, the sealing cap (not shown), which as heretofore indicated can be utilized to cover the upper portion of the bung-flange 20 by engagement with outer wall 27 of collar 26 thereof, is torn away, and the bung 41 within bung-receiving channel 40 is pushed down into the barrel.

5 A valve-connector 43 having a female bayonet joint element 44 is lowered through male bayonet joint notch 47 of mating male bayonet joint element or bayonet-flange 45 positioned on the uppermost portion 46 of bung-receiver 33, until female bayonet joint element 44 is below male bayonet joint element 45 (see Figures 3 and 4). The female bayonet joint element 44 is then turned clockwise until the female bayonet joint element 44 is engaged against stop 48 and assumes the position shown in Figures 5 and 6.

10 Valve mechanism 50 comprising conventional means for forcing the liquid contents of the container or the barrel outward therefrom is positioned in liquid-withdrawal position by threaded coupling element 51 having female threads which mate with correspondingly threaded male threads at the uppermost portion 52 of valve-connector 43. Coupling element 51 comprises an annular coupling flange or key 53 which sits within a groove 54 on the external wall of valve mechanism 50. By rotating coupling element 51 about the threaded connection at uppermost portion 52 of valve-connector 43, valve mechanism 50 can be made to seat on its bottom seat 55 on packing gland 49 which is seated on the topmost surface of male bayonet joint element 45 of bung-receiver 33. Packing gland 49 15 comprises gasket material, such as rubber or impregnated fabric, and serves to effect a fluid-tight and air-tight seating between bottom seat 55 of valve-mechanism 50 and the top surface of male bayonet joint element 45.

20 Valve mechanism 50 includes a riser-pipe 56 which extends through channel 40 in bung-receiver 33 virtually to the opposite extremity of the container.

25 The upper part of valve-mechanism 50 comprises a conventional air inlet conduit 57 consisting of a rubber or plastic air-hose engaged over ridges 58 on the stem of compressed air check-valve 59. Check-valve 59 is of conventional construction (for example, a Thomas valve) and permits flow of air under pressure inwardly through air inlet conduit 57 but prevents the flow of air in the opposite direction.

30 A positive head of air pressure can be built up within the container or drum by maintaining stop-cock 60 of the liquid withdrawal portion of valve mechanism 50 in closed position and introducing air through conduit 57 and check-valve 59. After the positive head of pressure has been built-up within the drum, the flow of air into the drum is terminated. On opening stop-cock 60 the liquid contents of the drum, such as beer, are removed through riser-pipe 56, stop-cock 60, elbow 61 and outlet conduit 62, which is inserted over the ridges 63 of a nipple 64 coupled to elbow 61.

35 Riser-pipe 56 is maintained in aligned position by means of gland packing 65 housed in gland-housing 66, gland packing 65 being urged against riser-pipe 56 by means of gland element 67. Gland packing 65 maintains a fluid-tight and air-tight seal between riser-pipe 56 and the outside atmosphere.

40 Valve mechanism 50 comprising the riser-pipe, outlet pressure head-forming means, outlet valve means and gland packing are of conventional construction and form no part of our invention. Thus, other conventional valve mechanism comprising different embodiments of the aforementioned elements can be substituted for that shown in Figure 1. For example, a separate conduit can be used to introduce the air from check-valve 59 into the barrel than is used to withdraw the liquid contents of the barrel and means for developing continuous air pressure within the barrel, permitting uninterrupted withdrawal of liquid therefrom can be secured.

45 After the container, drum or barrel has been emptied, the valve-mechanism 50 and valve-connector 43, are removed. Thus, coupling element 51 is uncoupled from valve connector 43 and withdrawn. Then valve-connector 43 can be rotated counter-clockwise and female bayonet joint element 44 withdrawn through notch 47, and the 50 valve-connector lifted free of the bung-receiver 33.

The empty drum or barrel can then be returned to the supplier, such as the brewery or the like, whereupon the locking ring 42 is disengaged from the locking groove 30 in the manner heretofore described, enabling the bung-receiver 33 to be disconnected from the bung-flange 20 and to be lifted out of the drum or barrel. This exposes the relatively large opening 25 in the bung-receiver 20 and facilitates cleaning of the drum or barrel.

After cleaning and inspection of the barrel have been effected, and the barrel re-filled with liquid, the bung-receiver 33 carrying a bung 41 is re-attached to the bung-flange 20, in the manner heretofore described and is again ready to receive the valve-connector 43 and valve-mechanism 50 for dispensing the liquid contents.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having described our invention, what we claim as new and desire to protect by Letters Patent is:

1. In a closure-and-tapping device for a barrel or the like, a bung-flange having an axial opening formed therein and having an upstanding collar, said collar being somewhat larger in diameter than said opening and being co-axial therewith, thereby providing a generally horizontal annular seating-surface peripherally of the upper end of said opening, said collar having a lower inner surface of generally polygonal outline and having an upper inner surface of generally circular outline and having an intervening locking-groove, said upper circular surface being provided with notches in vertical alignment with the corners of the polygonal surface, a bung-receiver having a passageway therein for removably receiving a bung, said bung-receiver including a generally cylindrical body adapted to fit within the opening in the bung-flange, said bung-receiver having an upper enlarged head of polygonal outline corresponding to the polygonal inner surface of said collar, a fluid-tight sealing joint including an O-ring mounted within a groove on said bung-receiver engaging said bung-flange, a resilient locking-ring capable of being deformed so as to reduce its normal diameter, said locking-ring being constructed and arranged temporarily to be positioned upon said head in compressed smaller-diameter condition while said bung-receiver is lowered into said bung-flange with the corners of the head fitting within the notches of the upper circular surface, said locking-ring being constructed and arranged to be set free of said head when said head is forced further downward into the lower polygonal surface, said locking-ring springing outwardly into the locking-groove in overlying relationship to the corners of the head whereby the bung-receiver is inter-locked with the bung-flange.

the bung-flange, said locking-ring being constructed and arranged to be contracted to remove it from the locking-groove thereby to free the bung-receiver and to permit it to be removed from the bung-flange.

2. A container including a barrel, a bung-flange mounted on an end wall of said barrel with the bore of said bung-flange coaxial with an opening in said barrel, the body of said bung-flange covering the edge of said barrel opening, said bung-flange having an axial opening formed therein and having an upstanding collar, said collar being somewhat larger in diameter than said opening and being coaxial therewith, thereby providing a generally horizontal annular seating-surface peripherally of the upper end of said opening, said collar having a lower inner surface of generally polygonal outline and having an upper inner surface of generally circular outline and having an intervening locking-groove, said upper circular surface being provided with notches in vertical alignment with the corners of the polygonal surface, a bung-receiver having a passageway therein for removably receiving a bung, said bung-receiver including a generally cylindrical body adapted to fit within the opening in the bung-flange, said bung-receiver having an upper enlarged head of polygonal outline corresponding to the polygonal inner surface of said collar, a fluid-tight sealing joint including an O-ring mounted within a groove on said bung-receiver engaging said bung-flange, a resilient locking-ring capable of being deformed so as to reduce its normal diameter, said locking-ring being constructed and arranged temporarily to be positioned upon said head in compressed smaller-diameter condition while said bung-receiver is lowered into said bung-flange with the corners of the head fitting within the notches of the upper circular surface, said locking-ring being constructed and arranged to be set free of said head when said head is forced further downward into the lower polygonal surface, said locking-ring springing outwardly into the locking-groove in overlying relationship to the corners of the head whereby the bung-receiver is inter-locked with the bung-flange, said locking-ring being constructed and arranged to be contracted to remove it from the locking-groove thereby to free the bung-receiver and to permit it to be removed from the bung-flange.
